UNITED STATES PATENT OFFICE.

WILLIAM C. BLUNDELL, OF LOS ANGELES, CALIFORNIA, ASSIGNOR OF ONE-HALF TO
MARY R. BLUNDELL, OF LOS ANGELES, CALIFORNIA.

WATER-INDICATING MEANS FOR STEAM-BOILERS.

1,267,622.

Specification of Letters Patent.

Patented May 28, 1918.

Application filed September 18, 1916. Serial No. 120,860.

To all whom it may concern:

Be it known that I, WILLIAM C. BLUNDELL, a citizen of the United States, residing at Los Angeles, in the county of Los Angeles and State of California, have invented a new and useful Improvement in Water-Indicating Means for Steam-Boilers, of which the following is a specification.

My invention relates to means for indicating the different stages of the water in steam boilers and the like and the primary object is to provide visible mechanical means in connection with the steam and water compartments of the boiler whereby the safety, danger and normal stages may be indicated at points exterior of and adjacent to the boiler.

Reference is had, in the consideration of this device, to a former invention of mine for which Letters Patent of the United States were granted to me on the 10th day of April, 1917, Serial Number 1,221,963, the present invention being a modification of the device shown in the former application for patent and embracing a number of valuable improvements which are not shown therein.

It is a further object of this invention, in addition to providing for mechanically indicating the maximum, normal and minimum stages of the water, to provide means whereby, when the boiler is being filled, the stages of the water in the boiler may be indicated as the water gradually rises, and further, to provide means at a point lower than the danger signal or stage, for indicating to the operator the necessity for continuing or discontinuing the firing of the boiler during the filling operation. Other objects 40 may appear in the detailed description which will follow.

Referring to the drawings, Figure 1 is a front elevation of the assembled indicating means. Fig. 2 is a plan of the same. Fig. 45 3 is a side elevation. Fig. 4 is a sectional elevation showing the connections with the boiler. Fig. 5 is a sectional plan of Fig. 1 on a plane cutting the indicator housing midway between the top and bottom. Fig. 50 6 is an enlarged front elevation of one of the indicators and the support therefor. Fig. 7 is a side elevation of Fig. 6.

Similar characters of reference are used in the several views of the drawings and in

the specifications for indicating the same or 55 similar parts.

As in the case of my former invention, hereinbefore referred to, I provide in this invention a plurality of expansion tubes which are supported at different elevations 60 on the exterior of the boiler and which are commonly connected with the steam and water compartments of the boiler in such a manner that the water from the boiler will rise in the common water column and in the 65 expansion tubes at or below the level of the water in the boiler, thus excluding the steam which is delivered to the tubes from the top of the boiler. The tubes above the water level, however, will receive the steam and 70 being heated from contact therewith will be expanded sufficiently to operate the mechanical signals which will be hereinafter fully described.

It is desirable to indicate the high, normal and low water stages of the water for damage may ensue from either of the extreme stages and the normal indicating means is provided for a safety signal when the water is at any level between the high 75 and low.

I provide a common water column 1 having a rear flat extension 2 to which is secured the slab 3 of wood or other suitable material by means of the bolts 4. The column 85 1 has two separate chambers, 5 and 6 formed therein and separated by means of the partition 7. The lower and longer chamber 5 is for accommodating the rise of the water in the column and is connected to the boiler 90 8 by means of a pipe 9 at the lower end of the column. The upper and relatively shorter chamber 6 is connected by means of the plug 10 and the pipe 11 with the steam compartment of the boiler, the pipe 11 being elevated sufficiently to insure a supply 95 of dry steam to the column.

Bosses 12, 13, 14 and 15 are formed on one side of the column 1 and similar bosses 16, 17 and 18 are formed on the opposite 100 side thereof, all of the bosses being internally threaded and having passages communicating with the chamber 5 of the column, the bosses 12 and 16, 13 and 17, and 14 and 18 being diametrically opposite on 105 the column and in the same transverse and longitudinal planes.

Each of the bosses 12, 13, 14 and 15 is pro-

vided with a drip valve 19 for discharging the water from the column under certain conditions, as for instance, when the boiler is being filled, all of these valves may be opened and as the water rises in the column, a portion of it will be drained off through the successive valves so as to indicate to the operator when the maximum level of the water has been attained, thus facilitating the filling of the boiler.

The bosses 16, 17 and 18, respectively, have lugs 20, 21 and 22 formed thereon which extend upwardly and are suitably perforated at the ends to receive the threaded ends of the outwardly and horizontally extended fulcrum rods 23, 24 and 25, each of these rods being adjustable relative to the lugs and firmly held thereon when properly adjusted by means of a pair of nuts 26 and 27, one of the nuts in each case being on one side and one on the other side of its respective lug for locking the rods thereto.

The bosses 16, 17 and 18 are provided respectively, with internally threaded nipples 28, 29 and 30 which receive and hold the expansion tubes 31, 32 and 33 in parallel relation with their respective rods. The outer ends of the expansion tubes are attached to the T fittings 34, 35 and 36 and the outer ends of these fittings have plugs 37, 38 and 39, respectively, inserted therein and extended outwardly therefrom, the ends of the plugs being conveniently flattened and slotted for purposes which will appear later on in the description.

The steam chamber 6 of the column 1 is connected with the T fittings 34, 35 and 36 by means of flexible tubes 40, 41 and 42 and a pipe 43 which is threaded into the boss 44 at its inner end. The upper ends of the tubes 40, 41 and 42 are connected by means of unions 45, 46 and 47 and L's 48, 49 and 50 to the T fittings 51, and 52 and the L 53 of the pipe 43, and the lower ends of the tubes are similarly connected by means of the unions 54, 55 and 56 and the L's 57, 58 and 59 with the T's 34, 35 and 36, for conducting the steam from the steam chamber of the column to the expansion tubes.

Bars 60, 61 and 62, which are necessarily of different length and are downwardly extended, are pivotally attached at their upper ends, respectively, to the flattened ends of the fulcrum rods 23, 24 and 25 by means of screws 63, or rivets, and at points slightly below the fulcrums the bars are pivoted by means of screws 64 to and are seated in the slots of the plugs 37, 38 and 39, so that when the steam enters the expansion tubes and causes the expansion thereof, the lower ends of the bars 60, 61 and 62 may be moved substantially, for operating the indicators.

Three indicators R, W and B which have relatively thin flat disks 65 supported on stems 66 are mounted in normally vertical

and parallel relation on the flat base or slab 3 within a suitable case 67 which is provided with an aperture 68 opposite the disks and a suitable glass or mica sheet 69 may be suitably held on the case so as to cover the opening and render the operation of the indicators visible to the operator. The case 67 may be suitably attached to the base 3 by means of screws 70, or otherwise.

The stems 66 of the indicators are threaded at their lower ends into the forward ends 71 of the bolts 72 which extend through the base 3 and are attached thereto by means of nuts 73. Hexagonal portions 74 are formed on the forward ends of each of the bolts 72 so that the bolts may be held against turning when the nuts are tightened. A sleeve 75 is provided for each of the indicators which is internally threaded and adapted to be screwed on the lower portions of the stems above the bolt ends 71. Lugs 76 are formed on the sleeves 75 which are perforated to receive the looped ends 77 of the rods 78, 79 and 80 connected respectively, with the lower ends of the bars 60, 61 and 62 at the opposite ends. Thus it is apparent that the indicators R, W and B may be adjustably connected with the expansion tubes 31, 32 and 33, so as to accommodate the action of the indicators to the movement of the tubes and to compensate for the difference in length of the operating bars, the sleeves 75 being adjustable on the indicator stems 66 and the stems being adjustable in the bolt ends 71. The indicator stems occupy substantially vertical positions when they are normal and all of the indicators move in the same direction when the tubes are expanded, namely, to the right, as shown in Fig. 1.

It will be observed that the bolts 72 are of different length and each of the indicators is in a different plane so that the connecting rods 78, 79 and 80 will not interfere with each other and with the indicators. The upper and central bars 60 and 61 are slightly deflected so as to clear the ends of the expansion tubes therebelow and the lower ends thereof are also in different planes corresponding to the planes of the indicators. A suitable aperture 81 is formed in the right hand side of the indicator case 67 to permit the operation of the rods 78, 79 and 80 therethrough.

In operation, when the level of the water in the boiler is above the expansion tube 31, this being the uppermost tube, or, when the boiler is cold, the position of the indicators R, W and B are as shown in Fig. 1, the tubes being incapable of expansion when they contain no steam. In the event of the first named condition the vertical positions of the indicators will indicate that the water level in the boiler is too high. When the stage of the water descends to a point below the upper tube 31, the steam will be admit-

ted thereto by means of the pipe 43 and the tube 40, and when the tube is sufficiently heated and expands the bar 60 is moved correspondingly, and the movement of this bar effects the movement of the blue indicator B through the medium of the link or rod 78, which indicator, when it assumes an inclined position toward the right hand side of the indicator housing, indicates that the water stage is high, but not too high.

Likewise, as the water descends further in the boiler and in the water column 1 connected therewith, the indicators W and R are successively operated by means of the bars 61 and 62 and the rods 79 and 80 connected therewith, respectively, when the tubes 32 and 33 are successively expanded. The movement of the indicator W to the right indicates that the stage of the water is normal, or at the intermediate point. The operation of the indicator R, which is the red or danger signal, indicates that the stage of the water is below the lowermost tube 33 and that more water should be supplied. It is designed to place the lowermost tube at a point sufficiently above the bottom of the water compartment in the boiler to provide ample time in which to replenish the supply of the water without undue haste but in the event that the signal should not be noticed at once, I provide the extra drip valve 19 which is attached to the boss 15 on the water column, and the operator may ascertain whether or not the stage of the water has reached a point below this valve by opening the valve. If no water may be drained off through the valve, the necessity for discontinuing the firing of the boiler is indicated.

It should be understood that the indicators operate in succession from the top to the bottom and from right to left, so that when the stage of the water is below the lowest of the tubes, all of the indicators will be in their inclined positions. The spacing of the tubes 31, 32 and 33 should correspond to the requirements in each particular case.

Having thus described my invention, what I claim as new and desire Letters Patent for, is:

1. A water indicating system for boilers comprising independently actuated indicators for the high, low and intermediate water levels in the boiler, separate steam and water connections leading from said boiler, expansion tubes in communication with and supported on said water connection, and independent connections between each of said expansion tubes and said steam connection, and means for operably connecting said tubes with said indicators, for the purpose set forth.

2. A water indicating system for boilers comprising a water column having separate water and steam connections with the boiler,

expansion elements communicating therewith at the high, low and intermediate water levels in the boiler, individual connections between said expansion elements and said steam connection, and a visible mechanical indicator connected for operation with and by each of said elements.

3. A water indicating system for boilers comprising a water column having separate water and steam chambers connected, respectively, with the water and steam portions of the boiler, expansion elements supported thereon and communicating with the water compartment thereof and independently connected with the steam compartment thereof, and a visible mechanical indicator for each of said expansion elements arranged for operation with and by the expansion of said elements.

4. A water indicating system for boilers comprising a water column having separate water and steam chambers connected, respectively, with the water and steam portions of the boiler, expansion tubes supported thereon and communicating at opposite extremities with said water and steam chambers, a housing supported on said column, a plurality of indicators mounted for operation in said housing, and means supported on the outer ends of each of said tubes connected with and for operating said indicators to correspond to the expansion of the tubes.

5. A water indicating system for boilers comprising a water column connected with the water and steam portions of the boiler and provided with expansion tubes arranged at different elevations thereon, connections between said tubes and the steam portion of the boiler, mechanical indicators respectively operably connected with said tubes, respectively for indicating the high, intermediate and low stages of the water, and valves at and below the planes of said tubes for further indicating the stages of the water therein.

6. A water indicating system for boilers comprising a water column connected with the water and steam portions of the boiler and provided with a plurality of expansion tubes supported at different elevations, and connections with the steam and water portions of the boiler, valves attached to said column opposite said tubes for draining the water therefrom, and indicators operably connected with said tubes for indicating the high, intermediate and low stages of the water in the boiler.

7. A water indicating system for boilers comprising a water column having separate steam and water compartments respectively connected with the steam and water portions of the boiler, expansion tubes supported thereon and communicating therewith at different elevations, means for ad-

mitting steam and water from the boiler to said tubes, valves also communicating therewith at different elevations, and indicators respectively associated with and operable by said tubes when the steam is admitted thereto, for indicating the successive stages of the water.

8. A water indicating system for boilers comprising a water column having separate steam and water chambers having connections, respectively, with the steam and water portions of the boiler, expansion tubes communicating with the water chamber at different elevations, means connecting each tube with said steam chamber, a plurality of drip valves communicating with said

water chamber at points respectively in the planes of said tubes and below the same for draining the water from the column, and indicators connected with and operable by said tubes respectively when the successive stages of the water in the boiler permits the admission of steam thereto, for visibly indicating the conditions at the boiler.

Signed at Los Angeles, in the county of Los Angeles and State of California, this 26th day of August, 1916.
